DESIGN FOR A COMBINED SCREW DRIVER AND NAIL EXTRACTOR

Thomas Rea, Detroit, Mich.

Application September 10, 1943, Serial No. 111,090

Term of patent 14 years

To all whom it may concern:

Be it known that I, Thomas Rea, a subject of the king of Italy, residing in the city of Detroit, County of Wayne, and State of Michigan, have invented a new, original, and ornamental Design for a Combined Screw Driver and Nail Extractor, of which the following is a specification, reference being had to the accompanying drawing, forming part thereof.

Fig. 1 is a perspective view of my combined screw driver and nail extractor;

Fig. 2 is a plan view of my combined screw driver and nail extractor;

Fig. 3 is a side view of my combined screw driver and nail extractor;

Fig. 4 is an end view looking toward the blade of my combined screw driver and nail extractor.

I claim:

The ornamental design for a combined screw driver and nail extractor, as shown.
